(57) **CLAIM**

The ornamental design for a light fixture, as shown and described.

DESCRIPTION

FIG. 1 is a top perspective view of a light fixture, showing our new design.

FIG. 2 is a right side view of the light fixture of FIG. 1, the left side view being a mirror image of the right side view.

FIG. 3 is a front view of the light fixture of FIG. 1.

FIG. 4 is a rear view of the light fixture of FIG. 1.

FIG. 5 is a top plan view of the light fixture of FIG. 1.

FIG. 6 is a bottom plan view of the light fixture of FIG. 1; and, FIG. 7 is a bottom perspective view of the light fixture of FIG. 1.

In the drawings, the broken lines form no part of the claimed design.

1 Claim, 5 Drawing Sheets
